[57] **CLAIM**

We claim the ornamental design for a device for attaching a shoe to an item of sports equipment, as shown and described.

DESCRIPTION

FIG. 1 is a right side elevation view of a device for attaching a shoe to an item of sports equipment, showing our new design;

FIG. 2 is a top plan view thereof;

FIG. 3 is a left side elevation view thereof;

FIG. 4 is a bottom plan view thereof;

FIG. 5 is a front end elevation view thereof; and,

FIG. 6 is a rear end elevation view thereof.
